UNITED STATES PATENT OFFICE

ALBERT J. HULSE, OF CHICAGO, ILLINOIS, ASSIGNOR TO H. A. BRASSET & COMPANY,
OF CHICAGO, ILLINOIS, A CORPORATION OF ILLINOIS

CHECKERBRICK AND CHECKERWORK CONSTRUCTION

Application filed August 20, 1928. Serial No. 300,901.

This invention relates to a new and improved checkerbrick and checkerwork construction and more particularly to such a construction adapted for use in hot blast stoves 5 for blast furnaces.

This invention is in the nature of an improvement or modification of the types of checkerbrick and checkerwork disclosed in the prior application, Serial No. 247,570, filed 10 January 18, 1928, by Herman A. Brassert, Charles W. Andrews and Albert J. Hulse, and application Serial No. 255,814, filed February 18, 1928, by Charles W. Andrews. The first application above referred to disclosed a form 15 of construction having removable filler brick in the passages of the main brick and the second application disclosed different types of integral portions on the brick extending into the passages.

20 In the present construction separate filler brick are used in the passages in the main brick and the brick are so constructed as to prevent displacement of the filler brick.

In hot blast stoves of usual design, the 25 interior of the stove is filled, except for the combustion chamber or vertical flue, with brick-work adapted to absorb and later give up heat in the different portions of the cycle of operation. The vertical passages through or between the brick have been made uniform in 30 dimension throughout the height of the stove. This uniformity of area is not desirable as it causes increased velocity of the gases in the upper portion of the stove. In the upper portion 35 of the stove the heating gases are at their greatest temperature and consequently their greatest volume, and in uniform passages their velocity must be greatest. In the same way, by the time the blast air has reached 40 the upper portion of the stove, it has reached its greatest heat, and consequently its greatest volume. This variation in velocity is undesirable for the purpose of efficient heat transfer.

According to the present invention filler 45 blocks are provided for insertion in the passages, both between the main checkerbrick and in the vertical passages in said brick. Brick of different size are provided so that the effective area of the passages may be varied in different portions of the furnace so as

to modify correspondingly the velocity of the gases passing through the passages.

It is an object of the present invention to provide new and improved checkerbrick for stoves and the like.

It is a further object to provide a construction in which the passage areas may be modified in different portions of the construction.

It is an additional object to provide a construction in which the main and filler brick 60 are fixed and stable in predetermined relation.

Other and further objects will appear as the description proceeds.

A preferred embodiment of the invention 65 has been shown in the accompanying drawings, in which—

Figure 1 is a fragmentary plan view, partly in section, showing a checkerwork formed according to the present invention;

Figure 2 is a perspective view of one of the small filler brick;

Figure 3 is a similar view of one of the middle size filler brick; and

Figure 4 is a similar view of one of the 75 large filler brick.

The main brick 11 are octagonal in cross section and the alternate lateral faces differ in size. The narrow faces 12 of adjacent brick engage each other when the brick are 80 built up into a checkerwork as shown in Figure 1. The wider faces 13 of adjacent brick form the intermediate vertical passageway 14. The brick 11 have the vertically extending passageways 15 formed therein. The main 85 portions of these passageways 15 are generally circular in contour with oppositely placed extensions 16 formed on lines which are tangential to the circle of the main portion of the passageways. These extensions render 90 the passageways non-circular in cross section.

The small filler brick 17 shown in perspective in Figure 2 have a central bulged portion 18, intermediate portions 19 with substantially parallel sides and ends 20 having 95 sloping or beveled edges. As clearly shown in Figure 1, the ends 20 fit into the extended portions 16 of the passageways 15 in the brick 11. This fit prevents the brick from being 100 improperly placed in the passageways, or

from turning after having been once put in place. This is highly important as it will be apparent that if two superposed filler brick 17 are placed at an angle to each other, there 5 will be a reduced area for passage of gas or air in the plane where the filler brick engage each other. Such a reduced area will slow up the passage of the fluids and be detrimental to the efficient operation of the stove. 10 This is prevented by the present construction.

An intermediate size of filler brick 21 is shown in Figure 3, this brick being similar to the brick of Figure 2, with the exception that the central bulged portion 22 is of greater 15 area. A large size filler brick 23 is shown in Figure 4, this brick having a still larger central portion 24. It will be understood that while only three sizes of brick have been shown, a greater or less number of different 20 sizes of brick may be used as desired.

As clearly shown in Figure 1, the filler brick 17, 21 and 23 may also be used in the 25 passages 14 formed between the brick 11. These passages 14 are square in cross section and the edges of the filler brick fit into the corners of the passages and prevent the brick from turning. The brick 11 are preferably so proportioned that the same filler brick may be used in the vertical passages 14 and 15.

30 In the construction of a checkerwork with the brick shown, the lowermost portion of the structure will be composed of brick 11 and 17, the next portion with brick 11 and brick 21, the next higher portion with brick 11 and brick 23 and the topmost portion with brick 11 only. This will give passageways having their greatest effective area at the top, and decreasing areas toward the bottom. A few 35 or greater number of different sections may 40 be provided as desired. The brick may be so designed in relation to the temperatures of the gases to be used and the rate of heat transfer as to give an approximately constant velocity throughout the height of the furnace. A 45 variable velocity may be had if desired to conform to differing rates of heat transfer in different portions of the structure due to a difference in the heat head between the gases or air and the bricks in such different 50 portions of the stove structure.

It will be apparent that if desired the brick 11 may be so placed in different portions of the structure that the filler brick in said different portions will be at right angles to each 55 other. If such portions are superposed, a space may be left without filler brick so that there will be no constriction of area between contacting, angularly related filler brick.

While one preferred form of construction 60 has been shown by way of illustration, the sizes, shapes and proportions of the brick may be changed to meet varying conditions and such changes and modifications are contemplated as come within the spirit and scope 65 of the appended claims.

I claim:

1. A checkerbrick having a longitudinal opening extending therethrough, said opening having longitudinally extending portions extending into the brick, whereby filler 70 brick may be located in the opening.

2. A checkerbrick having a longitudinal opening extending therethrough, said opening having diametrically opposed longitudinal portions extending into the brick, whereby 75 filler brick may be located in the opening.

3. A checkerbrick having an approximately cylindrical opening extending longitudinally therethrough, said opening having lateral extensions having walls formed on 80 intersecting planes substantially tangential to the cylinder.

4. A checkerbrick having an approximately cylindrical opening extending longitudinally therethrough, said opening having diametrically opposed lateral extensions having 85 walls formed on intersecting planes substantially tangential to the cylinder.

5. A checkerbrick octagonal in cross section, alternate faces of the octagon being similar in size, a longitudinal opening extending through the brick, said opening having diametrically opposed longitudinal portions extending into the brick, whereby filler 90 brick may be retained in predetermined position in the opening.

6. A checkerwork construction comprising a plurality of main checkbrick assembled to form vertically extending flues extending through superposed brick, said flues being non-circular in cross section, and filler brick 100 fitted into said flues for the full height of the brick and engaging the walls of the flues to prevent rotation of said filler brick.

7. A checkerwork construction comprising a plurality of main checkerbrick assembled to form vertically extending flues extending through superposed brick, said flues being non-circular in cross section, and filler brick 105 fitted into said flues and engaging the walls of the flues to prevent rotation of said filler brick, the filler brick in certain portions of said flues being greater in cross sectional area than those in other portions of said flues.

8. A checkerwork construction comprising a plurality of main checkerbrick assembled to form vertically extending flues extending through superposed brick, said flues being non-circular in cross section, and filler brick 110 fitted into said flues and engaging the walls of the flues to prevent rotation of said filler brick, the filler brick in lower portions of said flues being greater in cross sectional area than filler brick in portions of said flues 115 thereabove.

Signed at Chicago, Illinois, this 16th day of August, 1928.

ALBERT J. HULSE.
